UNITED STATES PATENT OFFICE.

EPHRAIM SMITH, OF PITTSBURG, PENNSYLVANIA, ASSIGNOR TO HUSSEY, BINNS & CO., OF SAME PLACE.

MOLD FOR CASTING SHOVEL-BLANKS.

SPECIFICATION forming part of Letters Patent No. 251,960, dated January 3, 1882.

Application filed December 1, 1880. (No model.)

To all whom it may concern:

Be it known that I, EPHRAIM SMITH, of Pittsburgh, in the county of Allegheny and State of Pennsylvania, have invented an Improved 5 Mold for Casting Shovel-Blanks and other similar Castings; and I do hereby declare that the following is a full and exact description thereof, reference being had to the accompanying drawings, making part of this specification—

Figure 1 being a face view of the inner surface of one of the halves or parts of the mold, the two parts being essentially alike; Fig. 2, a top view of the two parts forming the mold 15 put together, and showing the core used in position; Fig. 3, a vertical cross-section of the same, in a plane indicated by the line $x\ x$, Fig. 2; Fig. 4, a horizontal cross-section thereof, in a plane indicated by the line $y\ y$, Fig. 1; Fig. 20 5, a side edge view of the mold; Fig. 6, a view of the core separate; Fig. 7, a view in perspective of one of the shovel-blanks cast in the mold.

Like letters designate corresponding parts 25 in all of the figures.

The special purpose of my invention is to improve the iron molds for casting cast-steel shovel-blanks, and the process of casting the blanks therein, whereby a more perfect casting is produced for making a solid blade free 30 from imperfections, particularly at the lower end, which is especially necessary, and heretofore has been found to be difficult to accomplish. The mold and the method are employed 35 in connection with a peculiar core for forming the handle-socket in the blade and separating the two parts from which the handle-straps are formed. This core is made of a composition containing a combustible ingredient which 40 will ignite by the heat of the molten steel, and thereby have the effect to prevent the blowing out of the liquid metal or the imprisonment of gases therein, which otherwise would produce imperfections in the blanks.

45 In the drawings, A B represent the two parts of the mold, ordinarily made of cast-iron.

One of the essential features of my method of casting shovel-blanks is standing the mold upon the end in which the part of the blank 50 to form the lower end of the shovel-blade is

molded, as indicated in the several figures; but this arrangement of the mold is only essential in connection with the combustible core C, suspended in the upper or strap-forming part of the mold, at the sides of which core the molten steel is poured in casting. The edges of the core are held in recesses $a\ a$ in the two parts of the mold, and it is suspended by shoulders $b\ b$ thereon, resting on ledges $c\ c$ of the mold. To prevent its floating in the liquid metal as the mold fills, and consequent rising out of position, a wedge or nail, d , may be shoved in, or otherwise lightly inserted, between one of its edges and the adjacent mold at the top when the mold is ready for casting 65 into, as in Fig. 2.

The composition which I usually employ for the combustible core is as follows: sand, eleven parts, by measure; pitch, pulverized, one part, by measure; glue, when dry, one-fourth part, 70 by measure. The glue is first dissolved in about three times its weight of water. The sand and pitch mixed are then wet up with the glue-water, in a cold state, to prevent the softening and running of the pitch, and then molded 75 into cores. They are then dried in a suitable oven or chamber at a very low heat, and when thoroughly dry are ready for use.

Instead of pitch, rosin may be employed for the combustible ingredient of the cores, but it 80 does not work quite so satisfactorily as the pitch. Other materials equivalent in effect may be used, since I do not intend to confine myself to those above named, though I believe them to be preferable for the purpose to any other 85 known to me, the result designed to be attained being to have a combustible material in the core which will only ignite and gasify when subjected to the intense heat of the molten metal, and this at just the proper time and 90 in the proper quantity to supply the required amount of flame for the purpose—neither too rapid nor too abundant. When the molten steel is poured into the mold the core is ignited on its surfaces and produces smoke and 95 other products of combustion, which, escaping by the sides of the core, keep an interior vent open from the bottom thereof, by which all gaseous emanations from the liquid metal escape and allow a solid and perfect casting to 100

be produced. In order to further facilitate the escape of the smoke and gaseous products from the sides of the core, I form lateral openings *ff* in the adjacent surfaces of the mold-parts 5 *A*, *B*, preferably a little thicker than the core itself, as shown in Figs. 4 and 5, and extending outward from the edges of the core. These furnish free outlet to the smoke and other products at all times, unimpeded by the inpouring metal, which partially interferes with the upward escape of the said products.

When the narrow part of the cast blank which produces the shovel-straps is cooling in the mold it is liable to be pulled apart by the shrinking of the metal, the upper end solidifying first, and, by adhering to the mold at the top, drawing the inward part upward. I obviate this injurious tendency by making the mold somewhat narrower at the upper end, as 10 at *g*, Fig. 1, than at the lower end, *h*, of the narrow part, and gradually widening from the top downward, as indicated by parallel dotted lines *ww* in the same figure. The degree of this upward contraction of the mold is sufficient to prevent any part of the blank from 15 pulling upward far enough to rupture it. This shrinking and tightening up of the cooled blank in the mold, while the surplus metal of the ingate spreads somewhat over the top of the 20 mold, would cause the casting to lock in the mold if not obviated. I prevent the locking by forming inclinations *ii* extending from the upper, outer edges of the two mold-parts to the inner adjacent walls of the said parts, as shown 25 in Figs. 3 and 5. This form not only prevents the locking of the ingate-head over the ends of the mold parts, but causes the casting to loosen itself in the mold while cooling by its shrinking and drawing downward, and thereby acting 30 as a wedge to slightly separate the parts of the mold, which are not locked together, but simply stand side by side. The inclina-

tion of the upper end of the said parts also facilitates the pouring of the metal without waste.

By the term "combustible core" is to be understood a core which has a combustible ingredient sufficient to ignite and produce smoke and gaseous products of combustion while pouring the metal.

What I claim as my invention, and desire to 50 secure by Letters Patent, is—

1. A mold for casting shovel-blanks, constructed in two parts, *A*, *B*, having the wide or blade portion toward the bottom thereof and openings *ff* in the sides opposite to the narrow or strap portion, and provided with a core, *C*, supported in the narrow portion, the said core being composed of sand and a solid combustible material, in substantially the proportions set forth, all substantially as and for 60 the purpose herein specified.

2. The combination of a combustible core such as herein described and a mold, *A*, *B*, having its wide blade-forming part toward the bottom thereof, and the said core supported 65 in its narrow strap-forming part, substantially as and for the purpose herein specified.

3. The mold *A*, *B*, having vent-openings *ff* in its sides opposite to the narrow strap-forming interior thereof, in combination with the 70 combustible core *C*, having its side edges resting opposite to the said vent-openings, substantially as and for the purpose herein specified.

4. The mold parts *A*, *B*, having their upper 75 ends or faces, *ii*, inclined from their outside downward to their inner walls, substantially as and for the purpose herein specified.

EPHRAIM SMITH.
